UNITED STATES PATENT OFFICE.

EDWARD J. GULICK, OF ELKHART, INDIANA, ASSIGNOR TO C. G. CONN, LTD., OF
ELKHART, INDIANA, A CORPORATION OF INDIANA.

DESIGN FOR A DRUM-HOOP.

58,747.

Specification for Design.

Patented Aug. 30, 1921.

Application filed March 12, 1921. Serial No. 451,821. Term of patent 14 years.

To all whom it may concern:

Be it known that I, EDWARD J. GULICK, a citizen of the United States, residing in the city of Elkhart, county of Elkhart, Indiana, have invented a new, original, and ornamental Design for a Drum-Hoop, of which the following is a specification, reference being had to the accompanying drawing, forming part hereof.

On the drawing, Figure 1 is a top plan view of the hoop; Fig. 2 is a side elevation of the hoop showing one side thereof broken

away to show a section on the line 2—2 of Fig. 1; and Fig. 3 is a section taken on the line 3—3 of Fig. 1, which views clearly illustrate my new design for a drum hoop.

I claim:

The ornamental design for a drum hoop, as shown.

In testimony whereof I have hereunto affixed my signature this 10th day of March, 1921.

EDWARD J. GULICK.
